UNITED STATES PATENT OFFICE.

ARNOLD TURNER, OF DANBURY, CONNECTICUT.

POUNCING-PAD.

1,139,928.

Specification of Letters Patent.

Patented May 18, 1915.

Application filed March 31, 1911. Serial No. 618,233.

To all whom it may concern:

Be it known that I, ARNOLD TURNER, a subject of the King of Great Britain, and resident of Danbury, in the county of Fairfield and State of Connecticut, have invented certain new and useful Improvements in Pouncing-Pads, of which the following is a specification.

This invention relates to improvements in 10 hatting machinery and particularly to crown pouncers, so called, and more especially to pouncing pads, constituting a part of such crown pouncers.

My invention is equally applicable to rotary, and other forms of pouncing pads, but 15 for convenience of illustration I have shown it as applied to a pouncing pad, wherein the operative movement of the pad for carrying the finishing sand paper is reciprocating, in 20 a vertical direction.

The customary operation of most hat pouncing machines now upon the market is for the pads to begin their operation upon the side of the crown, and then work out 25 around the corners and toward the center of the tip. This operation is sometimes effected by moving the pouncer with relation to the rotating hat body, while in other types of machines the pouncer operates in substantially a fixed position, and the rotating hat 30 body is moved with respect to the operating pouncing pad.

My improved pad is adapted to be used in 35 connection with either of these types of machines, but was developed for use, and is illustrated as applied to the latter form of machine, and wherein the hat body is mounted upon a rotatable lathe the arm for which is pivotally supported upon a base in a manner to swing the hat block around with relation to the relative fixed position of the reciprocating pouncing pad.

The object of the invention is to improve 45 upon the various forms of pouncing pads, by making the same more resilient or yieldable in a way to obtain a lighter operation of the pad upon the delicate portions of the hat body, and especially to include means in the construction of such pouncing pads, whereby 50 they will not have to be helped over the square or corners of the hat, but will operate lighter upon such corners; and especially to provide means for avoiding all possibility of such pads cutting too freely upon the cor-

ners of the hat body as it runs from the side 55 over to the top of the crown.

With these and other objects in view the invention consists in the construction and novel combination and arrangement of parts hereinafter fully described, illustrated in the 60 accompanying drawings, and pointed out in the claims hereto appended, it being understood that various changes in the form, proportion, size and minor details of construction within the scope of the claims may be 65 resorted to without departing from the spirit or sacrificing any of the advantages of the invention.

Similar characters of reference denote like 70 or corresponding parts throughout the several figures of the accompanying drawings forming a part of this specification, and upon which,

Figure 1, shows a side elevation of a portion of a hat crown pouncing machine and 75 including a sectional elevation of a reciprocating type of pouncing pad, provided with my improvements. Fig. 2, is a front view of the pad shown in Fig. 1. Fig. 3, shows a top plan view of the machine with the pad 80 in position upon the side of the hat block for the beginning of an operation. Fig. 4, is a detail cross sectional plan view taken through the pouncing pad, on line 4 of Fig. 1 and showing the pad in the act of working 85 upon the corner of a hat block, and Fig. 5, is a detached plan view of a modified form of sandpaper, adapted to be used upon my pad.

Referring in detail to the characters of reference marked upon the drawings, 6 indicates the base of hat pouncing machine, 7 an arm pivotally mounted upon said base and adapted to be manually set (see Fig. 3) and then automatically moved around on the base, about one quarter of a rotation in one 90 direction. In this arm is journaled a lathe spindle carrying a chuck 8 upon its forward end, and on which the hat block 9 is clamped. The hat block is thus mounted substantially over the axis of pivotal movement of the 100 arm 7, thereby causing the hat to move around in a horizontal plane in addition to the rotary movement imparted to it by the lathe spindle. The hat body to be pounced being of a stiff hat kind, is previously stiffened, formed and fitted to a block 9, which serves to support it upon the lathe during 105 the pouncing operation. The blocks and hat

bodies are sometimes formed with a round crown, while others are made square or flat as illustrated in the drawings. The flat crown hats are usually considered the hardest to pounce owing to their having very square corners which makes it difficult for the pouncer to round such corners, or in other words to pass over the abrupt curve of the hat at the point where the side of the crown of the hat joins the top of the crown.

10 10 represents a bracket which is secured to the base of the machine and to which the lower end of an arm 11 is hinged. A swivel 12 is pivotally connected to the upper end of this arm 11 and serves to support a yoke 12^a bearing a supporting guide or member 13 having ways in which a plate 13^a secured to the rod 14 is reciprocatingly mounted. The lower end of this operating rod 14 is pivotally connected to an eccentric 15 mounted upon the outer end of a shaft which would be connected to an operative portion of the machine in a manner to be continuously rotated, to work the rod 14 and its plate in the 20 guide 13 for reciprocating the pouncing pad which is mounted upon said rod.

25 The pouncing pad 16 is hung through ball and socket joints 17 from end brackets 18 connected opposite the end portions of the pad and are secured to the rod in a way to permit the pad to swing on an axis parallel to the line of movement of the frame. The pad is thus carried by the frame and caused to alternately move up and down therewith, but in a manner to permit the pad to freely swing to one side or the other, better to conform to the position and shape of the hat body upon which it may be operating.

30 40 The pad further includes a metal base plate 19 having end plates 20 connected thereto and carrying the pivotal ball 17. Upon the face of this base plate is secured a soft pad 22 formed of sponge rubber, the 45 face of which is slightly oval from top to bottom, though flat across its face. The strips of sand paper 23 are cut to size and stretched longitudinally over the face of this soft rubber pad and has its opposite 50 end portions disposed in under the upper and lower clamping plates 24 which are held in position by means of clamping screws 25. The sand paper can thus be removed and new pieces inserted from time 55 to time as occasion may require, by simply loosening the thumb nuts of the screw 25 in a way to free the ends of the paper and permit its withdrawal.

55 The central portion of the pad proper including the sand paper 23 is cut away, to 60 form a hole 26 (see Fig. 2) to receive a guide, which as illustrated, includes a wheel 27, mounted in a holder 28, the rearwardly disposed end of which is slotted and loosely 65 hinged to a post 29 that is made adjustable

70 with respect to the yoke 12^a by means of a nut 21 housed in the yoke. This construction obviously leaves the guide free to move sidewise with the pad to conform to the position of the hat and also to be adjusted forward or backward and to or from the operating face of the pad by the nut 21, for the purpose of engaging the hat body with a suitable compression of the pad, but is thus not reciprocated with the pad. This adjustment thus regulates the possible amount 75 of yield of the operative face of the pad upon the hat body, and which, by reason of the presence of the guide, is prevented from cutting too hard upon the face of the hat 80 body and especially upon the corner portions of the crown as will be probably best understood from the illustration shown in Fig. 4, wherein the pad is shown in its operative position upon the corner of the hat 85 block and just in the act of running over from the side to the top. In some classes of work, for instance where the crowns are flat, as indicated by the block shown in the drawings, the guide would be adjusted out 90 farther and nearer the operating face of the pouncing pad, than would be necessary if it were a round crown that was being operated upon, for in the latter instance the change of position is more gradual than it 95 would be with the flat crown, where the hat surface of the operation of the pad is at all times broader and consequently less liable to be streaked or marked.

95 The absence of a portion of the sandpaper 100 in the central part of the operating face of the pad by the forming of a hole as in Fig. 2 serves also to lessen the possibility of streaking and injuring the corners of the hats as the crown passed around, since it 105 necessarily does less work upon these reduced round portions of the crown. I also reserve the right to use sand paper having either a reduced amount of or no sand upon the central surface of the face of the paper. 110 As indicated in Fig. 5 which does not contain a hole, but instead includes a central longitudinal smooth portion *a* and having the two side portions *b*—*b* sanded only. This form of paper can be manufactured in 115 continuous strips, or cut to lengths as required, and used with either a reciprocating pad like that shown in the drawings, or a rotary or other form of pad and with or without a guide.

120 While the guide is shown to include a wheel upon its outer end, to engage the hat body, yet it will be obvious that it is not essential to the successful operation of the device, for any suitable means constituting 125 a guide to be drawn over the hat body and to take up the pressure of the pouncing pad will come within the scope of my invention and I do not therefore wish to be limited in this particular.

The operation of the pouncer therefore, is as follows: The arm 7 is manually swung around upon its base 6 to the position shown in Fig. 3, whereupon the pouncer pad is brought to the position also shown in Fig. 3, said pad being held against the hat block, or body not shown, by means of a suitable spring or weight, not shown. The pad is then reciprocated vertically, while the lathe and hat block are being rotated and gradually moved around upon the base and back in line with the pad and its supports. While the hat block is thus rotating it also gradually moves around causing the pad to travel outward around the corners of the hat block and toward the tip of the crown. The pad is held against the block with a yieldable pressure in a way to form a soft, pliable and easy engagement of the pad with the hat thereby insuring a uniform pouncing operation upon the respective surfaces of the hat body. The guide wheel 27 serves not alone to protect the corners of the hat body from an excessive amount of work upon the corners, but also to limit the amount of pressure of the sand paper upon the quarters of the hat.

Having thus described my invention what I claim and desire to secure by Letters Patent is—

1. In a hat pouncing pad, the combination with a frame, and a suitable sand paper carried upon the pad, of a guide arranged centrally with respect to the pad and designed 35 to directly engage the hat body when the pad is compressed to limit the amount of pressure of the paper upon the hat.

2. In a hat pouncing pad, the combination with a reciprocating frame and pad, a smoothing paper carried thereby, of a guide arranged between the edges of the sand paper and adapted to be extended past the paper to engage the hat body.

3. In a hat pouncing pad, the combination 45 with a suitable frame, of a flexible pad mounted thereon, a piece of finishing paper, and a guide mounted centrally with the pad to engage the hat body.

4. A hat pouncing pad comprising a frame, a flexible pad mounted thereon, and having a hole therethrough, a smoothing paper placed upon the pad, and also having an opening therethrough, a guide extending through the pad and paper and so arranged 55 as to engage the hat body to relieve the pressure of the pad and to reduce the amount of work of the pouncer upon the corners of the hat.

5. In a hat pouncing pad, the combination 60 with a reciprocating pouncing pad, of a piece of operative finishing paper secured thereto and having the two side portions of its operative face sanded but having no sand intermediate of said sides.

6. A hat pouncing pad comprising a

frame, a flexible pad mounted thereon, a smoothing paper placed upon the pad, and a guide carrying a wheel to engage the hat to limit the pressure of the pad upon the hat.

7. A hat pouncing pad comprising a frame, a reciprocating flexible pad mounted thereon, a smoothing paper upon the face of the pad, a centrally arranged guide to engage the hat body when the pad is compressed and to limit the amount of pressure 75 of the smoothing paper upon the hat.

8. A hat pouncing pad comprising a frame, a flexible pad mounted thereon, a smoothing paper placed upon the pad, a guide carried by the pad and so arranged 80 as to engage the corner of a hat body between the operating surfaces of the paper when rounding the hat, and to reduce the amount of work of the pouncer upon the hat.

9. A hat pouncer comprising a pad having a hole in its central portion, a piece of finishing paper fitted upon the operative face of the pad, a guide wheel mounted in the hole and adapted to engage the corner 85 of the hat body when rounding the same. 90

10. A hat pouncer comprising a pad having a hole in its central portion, a guide mounted in the pocket and adapted to engage the corner of the hat body when rounding the same, a piece of finishing paper fitted 95 upon the face of the pad and having a hole therethrough to allow the guide to work therethrough.

11. A hat pouncer comprising a pad having a hole in its central portion, a piece of 100 finishing paper fitted upon the operative face of the pad, a guide mounted in the hole and adapted to engage the corner of the hat body when rounding the same, and means for adjusting the guide in and out 105 with respect to the face of the pad to vary the possible amount of pressure of the pad upon the hat.

12. A hat pouncer comprising a pad having a hole in its central portion, a piece of 110 finishing paper fitted upon the operative face of the pad, a guide mounted upon a holder arranged in the hole and adapted to engage the hat body, and a post to which the guide holder is pivotally connected. 115

13. A hat pouncer comprising a fixed member, a pad reciprocatingly mounted therein, a piece of finishing paper fitted upon the operative face of the pad, a non-yieldable guide carried by the fixed member and adapted to engage the hat body, and means for adjusting the guide with respect to the face of the pad to vary the possible amount of pressure of the pad upon the squares of the hat. 120

14. A hat pouncing pad comprising a fixed member, a pad operatively connected thereto, a sanded paper mounted upon the pad, a post adjustably mounted in the fixed member, a guide connected to the post, and 130

extended forward to the surface of the paper to engage a hat body.

15. In a hat pouncing pad, the combination with a suitable frame of a smoothing fabric having a portion cut away near the center for the purpose of lessening the amount of cutting at certain stages of the pouncing operation.

16. In a pouncing device, the combination with an operative pouncer tool, of a guide mounted centrally therein and adapted to engage the surface of a hat centrally of the operative engagement of the pad with the hat to limit the pressure of the tool upon the hat.

17. In a hat pouncing device, the combination of a reciprocating pouncing pad, a guide mounted in the pad and adapted to engage the surface of a hat centrally of the operative engagement of the pad with the hat to limit the amount of pressure of the pad upon the squares of a hat.

18. In a hat pouncing device, the combination of a reciprocating pad, a guide mounted in the pad and adapted to engage the surface of a hat centrally of the operative engagement of the pad with the hat to limit the amount of pressure of the pad upon the squares of a hat, and means for adjusting the said guide to change the limited amount of pressure of the pad upon the hat.

19. In a hat pouncing device, the combination of a reciprocating pad, an adjustable guide mounted centrally of and with respect to the operative face of the pad and adapted to operate in conjunction with the pad to limit the pressure of the operative face of the pad against the squares of a hat.

20. In a hat pouncing device, the combination with a supporting member, a reciprocating pouncing pad mounted therein, a guide mounted in the supporting member and adapted to operate upon the surface of a hat in conjunction with the operative face of the pad to limit the amount of pressure thereagainst.

21. In a hat pouncing device, the combination with a supporting member, a reciprocating pouncing pad mounted therein, a guide mounted in the supporting member and adapted to automatically reduce the amount of work of the pad upon the square of a hat when passing thereover.

22. In a hat pouncing device, the combination with a supporting member, a reciprocating pouncing pad mounted therein, a guide mounted in the supporting member to limit the amount of pressure of the pad

upon the sides of a hat and to automatically reduce the pressure and amount of work of the pad upon the squares of a hat.

23. In a hat pouncing device, the combination of a frame, a pad, a suitable finishing paper thereon, of a guide mounted centrally of and with respect to the face of the pad for automatically reducing the operation of the pad upon the square of a hat crown between the side and top.

24. In a hat pouncing pad, the combination with a suitable frame, of a flexible pad mounted thereon, a piece of finishing paper, a guide mounted centrally of and with relation to the operative face of the pad and adapted to engage a hat body in a manner to reduce the pressure of the pad upon the squares of a hat.

25. In a hat pouncing device, the combination of a rotatable hat support, a flexible pouncer pad, means for normally holding the pouncer pad in engagement with the hat body, a fixed guide for the pouncer pad to engage the hat body, and means for reciprocating the pouncer pad upon the hat body, and with relation to the guide.

26. In a hat pouncing machine, the combination of a rotatable hat support, a reciprocating pouncer pad, means for normally holding the pouncer pad in engagement with the hat body, and a centrally arranged guide fixed with relation to the pouncer pad to engage the hat body.

27. In a hat pouncing device, the combination of a reciprocating frame, an operating pad carried by the frame and connected to swing on an axis parallel with the line of movement of the frame, a guide projected from the face of the pad and adapted to move with the pivotal movement of the pad and adapted to engage a hat body when the pad is compressed.

28. In a hat pouncing device, the combination of a reciprocating frame, an operating pad pivoted to the frame, and adapted to swing on an axis parallel with the line of movement of the frame, a guide that is also connected to the frame and pivoted to move with the pivotal movement of the pad to engage a hat body when the pad is compressed.

Signed at Danbury, in the county of Fairfield and State of Connecticut, this twenty-ninth day of March, A. D. 1911.

ARNOLD TURNER.
